UNITED STATES PATENT OFFICE.

JOHN A. PURVES, OF SYRACUSE, NEW YORK, ASSIGNOR, BY DIRECT AND MESNE ASSIGNMENTS, TO FRED E. FRIEDMAN, OF SYRACUSE, NEW YORK.

ATTACHMENT FOR MILLING MACHINES.

Application filed June 2, 1921. Serial No. 474,459.

To all whom it may concern:

Be it known that I, JOHN A. PURVES, a resident of Syracuse, in the county of Onondaga and State of New York, have invented a certain new and useful Attachment for Milling Machines, of which the following is a specification:

This invention has for its object a particularly simple and efficient attachment for 10 milling machines and the like by which drilling, tapping, milling and similar operations can be performed; which attachment is particularly simple in construction, readily attached in position, and highly efficient 15 and durable in use and further which can be swung or swiveled to any angle to suit the convenience of the operator. The invention consists in the novel features and in the combinations and constructions hereinafter 20 set forth and claimed.

In describing this invention, reference is had to the accompanying drawings in which like characters designate corresponding parts in all the views.

Figure 1 is an elevation of this attachment, the same being shown as attached to the head of a milling machine.

Figure 2 is an elevation looking to the left in Fig. 1, parts being omitted.

Figure 3 is a plan view of this attachment, parts as the cap and driving sleeve being removed, and the tie rods being shown as spread outwardly and broken away.

Figure 4 is a sectional view on line 4—4, Fig. 3.

This attachment comprises generally, a body formed with an upright bearing and a transverse bearing intersecting one side of the upright bearing, a rotatable spindle arranged in the upright bearing, means for feeding the spindle vertically including a part located in the transverse bearing and also a non-rotatable part in the upright bearing and connected to the spindle to shift it axially, and means for attaching the body to a part as the head of a milling or other machine comprising a coupling member connected to the body by a swivel joint concentric with the axis of the spindle, and mechanism for detachably securing this coupling member to the head of a milling machine.

1 designates the body which includes a cylindrical central portion 2 and laterally extending hubs or bosses 3, the body being 55 formed with a central upright bearing 4

and a transverse bearing 5 which extends through the hubs or bosses 3.

6 designates the tool spindle rotatably mounted in the upright bearing 4, this spindle having a chuck 7 at its lower end in 60 which is carried a suitable tool as a drill 8.

9 is a driving tapered sleeve encircling the upper portion of the spindle 6 and being keyed or otherwise secured thereto to transmit rotary movement to the spindle 6, the 65 driving sleeve being inserted when the attachment is in use, in the tapered bore 10 of the rotatable spindle within the head 11 of a milling machine.

The means for feeding the tool spindles, 70 axially, relatively to the body 1 and the taper sleeve 9 comprises a part as the shaft 12 journaled in the transverse bearing 5 of the body 1 and having gear teeth 13 which mesh with rack teeth 14 provided on a non-rotatable sleeve 15 in the bearing 4 and also extending into the taper sleeve 9, the sleeve 15 encircling the spindle 6. The spindle 6 and sleeve 15 are held from relative axial movement by suitable means as collars 16 and 17 provided on the spindle 6 at the upper and lower ends of the sleeve 15. The shaft 12 is provided with suitable means for turning it as knurled wheels 18 mounted on the ends thereof, each wheel having suitable peripheral sockets 19 for receiving a rod as 20 which serves as a handle. Obviously, during turning of the shaft 12 the rotary movement thereof will be transmitted to the sleeve 15 to move the sleeve vertically and 80 through the sleeve 15 to the spindle 6 to feed the same axially while the spindle is rotating in the sleeve 15.

The shaft 12 is rotated in the direction opposite to that on which it is fed by the wheels 18 in any suitable manner, and as here shown, it is fed in a retrograde direction by means of a flat spiral spring 21 located in a head or a barrel 22 formed on one of the bosses or hubs 3, and connected at one end at 23 to the barrel 22 or a hub 24 located within the barrel and at its other end at 25 to one of the wheels 18 which serves as a closure for the outer end of the barrel.

The feeding movement of the spindle by the shaft 12 and against the action of the spring 21 is limited by suitable stop means here shown as a rack 28 slidable in a guide 29 extending transversely of the bearing 5 near the spring barrel 22 and meshing with 105

2
gear teeth on the shaft 12, and a stop 30 adjustably mounted on the rack 28 and arranged to engage the periphery of the spring barrel when the shaft 12 has been 5 rotated a sufficient distance to slide the rack to bring the stop 30 in contact with the spring barrel. The stop 30 may be of any suitable form, size and construction, and as here shown, includes a pair of collars slid- 10 able on the rack 28 and having screw threaded engagement at 31 with each other by means of which a fine adjustment is obtained, one of the collars having a pawl 32 which engages teeth of the rack 28 to obtain 15 an approximate adjustment.

33 designates a coupling member mounted on the body concentric with the spindle and connected to the body by a swivel joint, and as here shown, it is formed with a central 20 opening receiving a boss 34 provided on the upper side of the body concentric with the bearing 4 and it is held in position by a retaining ring or plate 35 arranged in a countersink 36 concentric with said opening, the 25 plate 35 being secured to the body or a boss 34 and overlying the bottom of the countersink, it being secured to the body by screws 37 extending through the plate and into the boss 34. The lower end of the driving sleeve 30 9 also extends into this countersink 36 and a nut 40 threads thereon. The upper surface of the coupling member around the countersink forms a bearing or seat for the lower end of the head 11 of the machine to 35 which this device is attached.

41 is a cap or collar for seating on the upper head of the head 11 of the milling machine, and 42 are tie rods pivoted at 43 to ears 44 provided on diametrically opposite 40 sides of the coupling member 43 and having their upper ends movable into slots 45 provided in lugs on the cap 41, suitable nuts 46 threading on the upper ends of these tie rods and serving to clamp the coupling member 33 and the cap 41 against opposite ends of the head 11 and the milling machine and thus securely attach the body 1 to the head of the milling machine, but owing to the swivel joint between the coupling member 45 59 23 and the body 1, the body can be swung to any angle to suit the convenience of the operator.

What I claim is:

1. An attachment for milling machines 55 comprising a body, a tool carrying spindle journaled in the body, means carried by the body for feeding the spindle axially, and means for attaching the body to a milling machine including a swivel joint concentric with the spindle and means for normally holding the body from swiveling movement, substantially as and for the purpose specified.

2. An attachment for milling machines 60 comprising a body formed with an upright

bearing, a rotary spindle in the upright bearing, a coupling member connected by a swiveled joint to the body concentric with the upright bearing, and means for attaching the coupling to the head of the milling machine and for normally holding the body from swiveling movement, substantially as and for the purpose set forth. 70

3. An attachment for milling machines comprising a body formed with an upright 75 bearing, and a transverse bearing intersecting one side of the upright bearing, a rotary spindle in the upright bearing, a coupling member connected by a swiveled joint to the body concentric with the upright bearing, means for attaching the coupling to the head of the milling machine and for normally holding the body and coupling member from swiveling movement, and means arranged in the transverse bearing 80 and coaxing with the spindle to feed and withdraw the same, substantially as and for the purpose described. 85

4. An attachment for milling machines comprising a body formed with an upright bearing, a tool spindle in the upright bearing, a coupling member connected to the body by a swivel joint concentric with the upright bearing and having a seat for one 90 end of the head of the milling machine, a member for seating on the other end of the head of the milling machine, and tie rods connecting said members and means for tightening the tie rods to hold the coupling member and body from swiveling movement, substantially as and for the purpose specified. 95

5. An attachment for milling machines comprising a body formed with an upright bearing, and a transverse bearing intersecting one side of the upright bearing, a rotatable tool spindle in the upright bearing, a coupling member connected to the body by a swivel joint concentric to the upright bearing and having a seat for one end of the head of a milling machine, a member for seating on the other end of the head of the milling machine, tie rods connecting said members, means for tightening the tie rods and holding the coupling member and body from swiveling movement, and means arranged in the transverse bearing for raising and lowering the tool spindle, substantially as and for the purpose set forth. 105 110 115

6. An attachment for milling machines comprising a body formed with an upright bearing and with the transverse bearing intersecting one side of the upright bearing, a rotatable spindle in the upright bearing, a sleeve in the upright bearing, the spindle being rotatably mounted in the sleeve and having means for holding it from axial movement relatively to the sleeve, the sleeve being formed with a rack, a shaft journaled 120 125 in the transverse bearing and having gear 130

teeth meshing with the rack, means for rotating the shaft, a coupling member mounted on the body concentric with the upright bearing and being connected to the body by a swivel joint, and means for attaching the coupling member to a milling machine head and for holding the coupling member and body from swiveling movement, substantially as and for the purpose set forth.

7. An attachment for milling machines comprising a body having an upright bearing and a transverse bearing intersecting one side of the upright bearing, a tool spindle rotatable in the upright bearing and mechanism for feeding the spindle axially including a shaft journaled in the transverse bearing, and means interposed between

the shaft and the spindle to shift the spindle axially during turning of the shaft, means for limiting the feeding of the spindle by 20 the shaft comprising a sliding rack extending transversely of said transverse bearing and intersecting one side of the same and coacting with the shaft to be moved end-wisely by the shaft during rotation thereof 25 and a stop on the rack arranged to engage the body when the rack has been fed a pre-determined distance, substantially as and for the purpose specified.

In testimony whereof, I have hereunto 30 signed my name at Syracuse, in the county of Onondaga and State of New York, this 1st day of June, 1921.

JOHN A. PURVES.
